HYDRAULIC PRESSURE MULTIPLYING
MECHANISM

Herbert E. Page, Syracuse, N. Y.

Application May 4, 1938, Serial No. 206,006

7 Claims. (CL 60—52)

This invention relates to hydraulic pressure multiplying mechanisms, and has for its object a simple construction by which a part to be actuated or driven member is quickly moved or operated up against the work by one or two movements of the operating lever, and after the driven member encounters the resistance of the work, heavy pressure is applied by successive operating movements of the prime mover.

10 It further has for its object a hydraulic pressure multiplying mechanism embodying a shiftable body formed with at least two piston chambers, pistons working in the chambers, one of the pistons being a prime mover, which may be actuated in any suitable manner, or by hand, and a transfer passage between the chambers having means, as a spring-pressed valve therein with sufficient resistance to normally prevent the transfer of the hydraulic liquid from the smaller or prime mover chamber to the large or power chamber and to permit the flow of the hydraulic liquid from the prime mover to the power chamber, when the driven or actuated part encounters resistance, so that upon preliminary operation, the driven or actuated part is quickly operated by one or two movements of the prime mover to take up the lost motion between it and the work, and thereafter upon successive reciprocations of the prime mover, the liquid from the prime mover chamber is pumped into the larger power chamber, and the pressure multiplied in the power chamber, to cause the actuated part to apply heavy but slower pressure to the work.

25 I have here illustrated my invention as applied to a hydraulic lifting jack.

30 The invention consists in the novel features and in the combinations and constructions hereinafter set forth and claimed.

In describing this invention, reference is had to the accompanying drawing, in which like characters designate corresponding parts in all the views.

Figure 1 is a longitudinal sectional view through the pressure multiplying mechanism.

Figure 2 is a side elevation of a mechanism embodying a slightly modified form or reverse of the exemplification shown in Figure 1.

1 designates a suitable body, which is mounted to shift, and here shown to shift rectilinearly. 2 designates a driven part or part to be actuated, this being shown as a lever pivoted at 3 to a fixed point or a shaft mounted in the frame, not shown, of the machine or apparatus in which the mechanism is embodied. This lever is provided with a suitable head, not shown, pressing

against the work to which the pressure is to be applied, or, in the case of a jack, against the article to be lifted.

The body 1 is formed with piston chambers 4 and 5 extending lengthwise thereof or parallel to the direction of the shifting movement of the body 1, these chambers being of different diameters, the chamber 5 of larger diameter being a power chamber for applying heavy pressure. 6 and 7 are pistons working respectively in said chambers 4 and 5. The body 1 is also formed with a reservoir 8 for a hydraulic liquid which communicates through passages 9, 10, 11, with the piston chambers 4, 5 in order to permit the hydraulic fluid to circulate or run or transfer freely from the reservoir to the piston chambers. These pistons are provided with means or are so constructed as to permit the flow of the fluid from the rear sides to the front or pressure sides thereof, and prevent the flow from the pressure sides to the rear sides. As shown, these pistons are formed with the usual flexible cup-shaped heads. The reservoir is formed with a suitable filler opening 12 closed by a closure 13.

14 is the transfer passage between the chambers 4 and 5, this having yielding means therein for normally preventing the transfer of the fluid from the prime mover chamber 4 to the power chamber 5, and operable to yield and permit said transfer when the work lever 2 encounters resistance. This means, as here shown, is a spring-pressed valve 14a pressing against its seat 15 by a spring 16, the tension of which may be adjusted by means of a suitable adjusting screw or plug 17. The prime mover piston 6 has its rod 18 connected to a suitable actuator 19, this being shown as a lever pivoted at 20 to a shaft on a frame, not shown, and having an arm 21 connected through a link 22 to the outer end of the piston rod 18. A suitable returning spring 23 is connected to the lever 19 or the arm 21 thereof, and a stop-pin 24 fixed to the frame, not shown, limits the retrograde or return movement of the lever 19.

In the form shown in Figure 1, the power piston 7 has its rod 25 pivoted or anchored at 26 to a shaft on the frame, so that the piston 7 remains stationary and the body 1 shifts, when heavy pressure is being applied. This is the reverse of the construction shown in Figure 2, in which the power piston is shiftable relatively to the body. The relative movement of the body and the piston 7 is transferred to the driven part or lever 2 through suitable mechanism, and in the form shown in Figure 1, the lever 2 has an arm 27

pivoted at 28 to an arm 29 at one end of the shiftable body 1. Means is provided for returning the driven part 2 to its starting position, as well as all other moveable parts of the machine or mechanism, and also releasable means is provided for holding the driven part or lever 2 in its operated position. The returning means includes a spring 30 anchored at one end at 31 to a pin on the frame and at its other end at 32 to the shiftable body 1. The releasable holding means, as here shown, comprises a valve 34 in a chamber 35 formed in the body 1 in communication with the reservoir 8 and the piston chambers 4, 5 and normally closing ports or passages 36, 37 leading from the pressure sides of the chambers 5, 4 into the chamber 35 or into the reservoir, this valve being normally closed and operable into open position to release the pressure in the power chamber 5 and prime mover chamber 4 to permit the spring 30 to react and return the parts to their starting positions. The valve 34 is here shown as carried by a stem 38 threading through the rear end of the body 1 and having a handle 39 at its outer end.

In operation, upon forward movement of the arm 21, that is, movement to the right, against the action of its returning spring 23, this being effected by moving the operating lever 19 to the left, the prime mover piston 6 will be moved in the piston chamber 4, to the right, but as the oil has no means of escape from the chamber 4 on the pressure side thereof, and the valve 14^a is held seated by its spring 16, the body 1 is shifted to the right, and hence the driven part or lever 2 shifted from its starting position or full-line position. When, however, the lever 2 encounters the resistance of the work and the lever 19 is again actuated or reciprocated, the hydraulic fluid passes the valve 14^a through the transfer passage 14 into the larger power chamber 5, reacts against the piston 7, which is held stationary, and effects an additional movement of the body 1 to the right. The spaces on the pressure sides of the pistons are always kept filled by reason of the fact that the oil can pass from the rear side to the pressure side of the piston or the cup-shaped head of the piston 7. As the chamber 5 is of greater capacity than the chamber 4, repeated movements of the piston 6 can be used to build up the pressure in the chamber 5 required to be applied to the lever 2 to perform its work. Because the release valve 34 is closed, the pressure is locked in the pressure ends of both the piston chambers 4, 5, and hence the lever 2 held in any operated position.

However, upon opening of the valve 34 by turning the handle 39, the pressure in the pressure ends of the chambers 4, 5 is released through the passages 36, 37 to the reservoir, so that the re-turning spring 30 is free to react and restore all parts to their starting positions.

In Figure 2, a construction is shown in which the reservoir and piston chambers, instead of being bored in the block are separate elements and interconnected, and also the smaller or preliminary closing cylinder only is shiftable, while the power cylinder is stationary or held from shifting movement and the power piston is movable.

In Figure 2, 80 designates the reservoir; 40 the prime mover piston chamber; 50 the power piston chamber; 60 the prime mover piston; and 70 the heavy pressure or power piston, and the stem 71 thereof is pivoted at 72 to the arm 210 of the actuated part or lever 200. 300 designates the returning spring, corresponding to the spring

30. 140 designates the transfer passage or conduit corresponding to the transfer passage 14 (Figure 1), and 141 the control valve therein, corresponding to the valve 14a. The reservoir 80 is connected to opposite ends of the cylinder 50 through passages or conduits 90, 91, conduit 90 having a manually operable valve 92 therein. The reservoir 80 is connected to the rear end or the left end of the piston chamber 40 through a flexible pipe 110. The conduit 140 is also flexible. The pressure side or right end of the piston chamber 40 is connected to the reservoir through a conduit 360 which is connected to the conduit 140 between the check valve 141 and the cylinder 40. The conduit 360 has a release valve 340 therein. The cylinder 50 is pivoted at 260 to the frame. Because of the flexible conduits 110 and 140, the cylinder 40 can shift relatively to the cylinder 50 and reservoir 80.

In operation, the piston rod 180 of the prime mover piston 60 is connected to an arm of the operating lever 190, as in Figure 1. The cylinder 40 at its right end is pivoted at 40^a to an arm 40^b at an angle to and rigid with the arm 210 of the actuating member or lever 200. The piston rod 71 of the power piston 70 is also pivoted to the arm 210. As the cylinder 50 is anchored or pivoted at 260, the piston 70 moves relatively to the cylinder, instead of the cylinder moving relatively to the piston, as in Figure 1. 30

In operation, upon movement of the handle end of the lever 190 to the left (Figure 2), the piston 60 is moved to the right in the cylinder 40, and as the valve 141 is held closed by its spring, when there is no resistance to the lifting arm 200, the cylinder 40 shifts to the right, this being permitted by the flexible pipes 110 and 140, and thrusts against the arm 40^b lifting the arm 200 against the work. This movement from the full-line position (Figure 2) toward the dotted line 40 position pulls the piston 70 through the rod 71, moving it toward the right end of the cylinder 50, the oil displaced passing the cup-shaped head of the piston 70 into the left hand end of the cylinder 50. When the arm 200 encounters the 45 resistance of the work, movement of the actuating lever 190 and hence the piston 60, causes the oil to overcome the spring of the check valve 141 and pass through the pipe 140 into the left hand end of the cylinder 50, so that repeated 50 operations of the hand lever 190 and piston 60 pumps the oil into the pressure end of the cylinder 50, moving the piston 70 to the right in short steps and transferring the movement through the piston rod 71 to the arm 210 of the lever 200, thus applying heavy pressure. 55

During these operations, the valves 340 and 92 are closed, and to release the pressure in the cylinders, these valves are opened and the parts are returned to their starting positions by the spring 300.

What I claim is:

1. In a pressure multiplying mechanism, the combination of a shiftable body element including piston chambers, and a reservoir for a hydraulic fluid for supplying the fluid to the chambers, pistons working respectively in the chambers, a part to be actuated, one of said pistons being a prime mover operating to shift the body, a transfer passage connecting the chambers, yieldable means for restraining the movement of the fluid from the prime mover chamber to the other chamber, operable to close said passage during preliminary movement of the prime mover for freely actuating said part, and to yield- 75

ingly open when said part encounters resistance causing the fluid to be forced by the prime mover, through the transfer passage into the other chamber and effect relative movement of the body and the piston in said other chamber, and means for transferring the shifting movement of the body and said relative movement to said part.

2. In a pressure multiplying mechanism, the combination of a body element including piston chambers, and a reservoir for a hydraulic fluid for supplying the fluid to the chambers, pistons working respectively in the chambers, a part to be actuated, one of said pistons being a prime mover operating to shift the body, a transfer passage connecting the chambers, yieldable means for restraining the movement of the fluid from the prime mover chamber to the other chamber, operable to close said passage during preliminary movement of the prime mover, for freely actuating said part and to yieldingly open when said part encounters resistance causing the fluid to be forced by the prime mover through the transfer passage into the other chamber and effect relative movement of the body and the piston in said other chamber, means for transferring the shifting movement of the body and said relative movement to said part, and circulating passages between the chambers and the reservoir, said pistons being constructed to permit flow of the liquid from the rear side to the pressure side thereof and prevent the flow from the pressure side to the rear side.

3. In a pressure multiplying mechanism, the combination of a shiftable body element including piston chambers, and a reservoir for a hydraulic fluid for supplying the fluid to the chambers, pistons working respectively in the chambers, a part to be actuated, one of said pistons being a prime mover operating to shift the body, a transfer passage connecting the chambers, yieldable means for restraining the movement of the fluid from the prime mover chamber to the other chamber, operable to close said passage upon preliminary movement of the prime mover, for freely actuating said part, and to yieldingly open when said part encounters resistance causing the fluid to be forced by the prime mover through the transfer passage into the other chamber and effect relative movement of the body and the piston in said other chamber, means for transferring the shifting movement of the body and said relative movement to said part, a returning spring arranged to return the actuated part and the other movable parts of the mechanism to their starting positions, and releasable means for holding the same in their operated positions.

4. In a pressure multiplying mechanism, the combination of a body element including piston chambers, and a reservoir for a hydraulic fluid for supplying the fluid to the chambers, pistons working respectively in the chambers, a part to be actuated, one of said pistons being a prime mover operating to shift the body, a transfer passage connecting the chambers, yieldable means for restraining the movement of the fluid from the prime mover chamber to the other chamber operable to close said passage during preliminary movement of the prime mover for freely actuating said part, and to yieldingly open when said part encounters resistance causing the fluid to be forced by the prime mover through the transfer passage into the other chamber and effect relative movement of the body and the piston in said other chamber, means for trans-

ferring the shifting movement of the body and said relative movement to said part, a release valve operable to trap the pressure in said chambers, and operable to release the same, and a returning spring for returning the movable parts 5 of the mechanism to their starting positions.

5. In a pressure multiplying mechanism, the combination of a shiftable body element formed with piston chambers extending in a general direction parallel to the shifting movement of the body, and a reservoir for a hydraulic fluid for supplying the fluid to said chambers, the chambers being of different diameters, pistons working respectively in the chambers, a part to be actuated, the piston working in the smaller 10 chamber being a prime mover operating to preliminarily shift the body, a transfer passage connecting the chambers, yieldable means for restraining the movement of the fluid from the prime mover chamber to the other chamber operable to close said passage during preliminary movement of the prime mover for actuating said part and yieldingly open when said part encounters resistance, causing the fluid to be forced by the prime mover through the transfer passage to the larger piston chamber and effect relative movement of said part and the piston in the larger chamber, means for transmitting the movement of the body effected by the prime mover piston and said relative movement to the 15 part to be actuated, and means tending to return the part to be actuated and the movable parts of said mechanism to their starting positions, and releasable means for holding the same 20 in their operated positions.

6. In a pressure multiplying mechanism, the combination of a shiftable body element including piston chambers, and a reservoir for a hydraulic fluid for supplying the fluid to the chambers, pistons working respectively in the chambers, a part to be actuated, one of said pistons being a prime mover operating to preliminarily shift the body, a transfer passage connecting the chambers, yieldable means for restraining the movement of the fluid from the prime mover 25 chamber to the larger chamber, operable to close said passage upon preliminary movement of the prime mover for freely actuating said part, and to yieldingly open when said part encounters resistance causing the fluid to be forced by the prime mover through the transfer passage into 30 the larger chamber and effect relative movement of the body and the piston in said larger chamber, means for transferring the shifting movement of the body and said relative movement to said part, a returning spring arranged to 35 return the actuated part and the other movable parts of the mechanism to their starting positions, and releasable means for holding the same in their operated positions.

6. In a pressure multiplying mechanism, the combination of a shiftable body element including piston chambers, and a reservoir for a hydraulic fluid for supplying the fluid to the chambers, pistons working respectively in the chambers, a part to be actuated, one of said pistons being a prime mover operating to preliminarily shift the body, a transfer passage connecting the chambers, yieldable means for restraining the movement of the fluid from the prime mover chamber to the larger chamber, operable to close said passage upon preliminary movement of the prime mover for freely actuating said part, and to yieldingly open when said part encounters resistance causing the fluid to be forced by the prime mover through the transfer passage into the larger chamber and effect relative movement of the body and the piston in said larger chamber, means for transferring the shifting movement of the body and said relative movement to said part, a returning spring arranged to return the actuated part and the other movable parts of the mechanism to their starting positions, a release valve operable to trap the pressure in said chambers and to release the same, and a returning spring for moving the part to be actuated and other movable parts of the mechanism effected by the operation of the prime mover to their starting positions.

7. In a pressure multiplying mechanism, the combination of a shiftable body element including piston chambers of different diameters, and a reservoir for a hydraulic fluid for supplying the fluid to the chambers, pistons working respectively in the chambers, a part to be actuated, the piston in the smaller chamber being a prime mover operating to preliminarily shift the body, a transfer passage connecting the chambers, yieldable means for restraining the movement of the fluid from the smaller chamber 70

to the larger chamber operable to close said passage upon preliminary movement of the prime mover for freely actuating said part, and to yieldingly open when said part encounters resistance 5 permitting the fluid to be forced by the prime mover through the transfer passage into the larger chamber and effect relative movement of the body and the piston in the larger chamber, means for transferring the preliminary shifting 10 movement of the body and said relative movement to said part, the body being provided with

circulating passages between the chambers and the reservoir, pistons including means to permit the flow of liquid from the rear side to the pressure side thereof and prevent the flow in the reverse direction, means tending to return the actuated part and other movable parts of the mechanism to their starting positions, and releasable means for holding the same in their operated positions. 5
